CARBURETOR FOR INTERNAL COMBUSTION ENGINES

Ignaz Schorsch, Prague, Czechoslovakia

Application March 7, 1936, Serial No. 67,729
In Germany March 8, 1935

6 Claims. (Cl. 261—51)

The present invention relates to improvements in carburetors for internal combustion engines and has for its object to provide a carburetor with which a complete mixture of fuel and air is ensured by means of mechanical disintegration of the fuel drawn in.

According to the invention, the fuel is no longer sprayed into the flow of air drawn in as in the known carburetors, but is conducted, in a path having multiple diversions, to the first of a plurality of mixing and atomizing chambers which are telescopically arranged one behind the other in the direction of flow of the air entering as a result of suction action, the said chambers being open against the direction of flow of air, that is on the air intake side, and covered on the throttle side by means of fine mesh wire gauze or the like. This arrangement ensures a complete mixture of fuel and air which results in increased safety, longer life, and enables accurate regulation, combined with fuel economy and instant starting of the engine.

A further object of the invention is to provide a device for regulating the quantity of fuel in a distinct proportion to the quantity of air flowing in as a result of suction action. This regulating of the fuel is effectuated according to the invention in a conducting bush the end of which lies against the atomizing chambers being controlled by a valve, but the flowing through sectional area of this bush is regulated by a valve needle lying in this bush. The mantle of this needle has a generatrix, which is formed according to a distinct curved line, so that the quantity of fuel is no more directly regulated by the lifting distance of the valve from its seat but merely by the ring-like flowing through section constituted by the needle and the inner side of the bush.

In order that the invention may be more clearly understood two embodiments thereof will now be described by way of example, with reference to the accompanying drawing wherein, Fig. 1 is a vertical section of one embodiment, Fig. 2 a section on the line II—II of Fig. 1, and Fig. 3 a plan and part section on the line III—III of Fig. 2. Fig. 4 is a part vertical section of the other embodiment. Fig. 5 is a cross sectional view taken on the section line V—V of Fig. 4.

Referring to the drawing the carburetor consists of two parts 6, 7, joined together by means of a web 5 and communicating through a tube 26, the part 6 being equipped for the adjustable admission of the fuel and the part 7 for the formation of the mixture of fuel and air and 55 for conveying the mixture.

The inlet aperture 8 for the fuel, in the part 6 is provided with a filter 9 and is continued in the form of a horizontal passage 10, from which the fuel reaches a vertical channel 12, the quantity passing being regulated by a needle 11. The inner end of this channel 12 corresponds with an aperture 13 in the shell part 15 of a bush 15, 16. The inner wall of the bush 15, 16 is provided with a valve seating 14, so that the inner diameter of the part 15 of the bush is smaller than the inner diameter of the part 16 of said bush.

The valve body 17 has a needle 18 projecting into the closed-off bush part 15 and tapering off towards its end, and has a spindle 19 located within the bush part 16, against which spindle 15 presses a spring 20 which is supported against the cover 21 of the bush part 16. Through the cover 21 passes the stem 22 of the spindle 19.

The needle 18 has a generatrix, which is formed according to a distinct curved line. Thus by 20 lifting the valve a ring like flowing through section for the fuel is formed between the needle and the inner wall of the bush-part 15 before the valve and so conditions are performed for conducting such a quantity of fuel as is necessary to be mixed with the air taken in by suction-action.

In the vicinity of the valve seating 14, the inner wall of the bush part 16 is provided with an annular groove 23 which is continued in the 30 form of an aperture through the bush, the aperture corresponding with an aperture 24 provided in the web 5 and opening into the part 7.

In the part 7 is a bush 25 provided with an aperture concentric with the aperture 24 in the web 5 and in which is fitted the radial part of an elbow tube 26 which forms an extension of the aperture 24. At the horizontal part of the elbow tube which lies in the axial direction of the part 7, is secured a boss member 27 of a fork 28 extending out from this in an axial direction. The insides of the fork legs are stepped, and each step length 29 terminates in a short slot 30 in the adjoining part of the fork leg. In these slots fit the ends of hollow truncated conical members 31, 32, 33, 34, the ends of which projecting into the range of the next step are permeably closed by narrow mesh wire gauze 35.

In this manner a plurality of chambers are 50 formed in the part 7 which chambers fit one inside the other telescopically, and are open at one end and permeably closed at the other end. Into the first of these chambers the fuel is conducted in a regulated quantity through the elbow tube 55

26, whilst the air is led through the funnel 50 of the air intake, into said chambers.

By means of this device the formation of the mixture of fuel and air is divided between the 5 chambers 31—34, and it will be readily appreciated that in consequence of the action of the wire gauze 35 successive atomizations of the fuel are effected, which results in an intimate mixture of the fuel with the air.

10 The entrance of the fuel and of the air is brought about by means of the vacuum prevailing in the carburetor chamber, which vacuum is regulated in the known manner by means of the throttle valve 36 mounted in the part 7.

15 In order to adjust the valve body 17 for a certain quantity of fuel in dependence upon the position of the throttle valve, the following arrangement is for example provided: On the shaft of the throttle valve 36 is fitted a lever 37; which 20 is actuated in the well known manner from the driver's seat of the vehicle. On this lever 37 is linked a lever 38, which is connected by means of a screw to an auxiliary piston 40 guided in the part 6 and loaded with the spring 39. The rod 25 41 of this piston is connected to the stem 22 of the valve spindle 19 by means of a tie member 51. In this way is effected a displacement of the valve body 17 exactly in an axial direction.

For the sake of completeness it may be added 30 that the part 6 may be provided with an auxiliary air inlet 42 adjustable by means of the screw needle 52.

The construction of the carburetor illustrated in Figure 4 differs from that described above, 35 only by reason of the fact that the mixing chambers 31', 32', 33', are cylindrical instead of being of truncated cone shape. The latter shape is to be employed for specifically heavier fuels, the former (Figure 4) for specifically lighter 40 fuels. There will also be cases in which both forms of the chambers can be advantageously used in one carburetor, similarly the number of these chambers may vary according to circumstances.

45 What I claim is:

1. A carburetor for internal combustion engines comprising a throttle, an air intake, a plurality of mixing and atomizing chambers located between said throttle and said air intake and arranged telescopically one behind the other, said 50 chambers being open on the air intake side and closed by permeable means on the throttle side and means for leading fuel to the mixing and

atomizing chamber located nearest to said air intake.

2. A carburetor for internal combustion engines comprising a throttle, an air intake, a plurality of mixing and atomizing chambers located 5 between said throttle and said air intake and arranged in overlapping relation, said chambers being open on the air intake side and closed by permeable means on the throttle side and means for leading fuel to the mixing and atomizing 10 chamber located nearest to said air intake.

3. A carburetor for internal combustion engines comprising a throttle, an air intake, a plurality of mixing and atomizing chambers located 15 between said throttle and said air intake and arranged telescopically one behind the other, said chambers being of truncated conical shape and being open on the air intake side and closed by permeable means on the throttle side and means for leading fuel to the mixing and atomizing 20 chamber located nearest to said air intake.

4. A carburetor for internal combustion engines comprising a throttle, an air intake, a plurality of mixing and atomizing chambers located 25 between said throttle and said air intake and arranged telescopically one behind the other, said chambers being of cylindrical shape and being open on the air intake side and closed by permeable means on the throttle side and means for leading fuel to the mixing and atomizing 30 chamber located nearest to said air intake.

5. A carburetor for internal combustion engines comprising a throttle, an air intake, a plurality of mixing and atomizing chambers located 35 between said throttle and said air intake and arranged in overlapping relation, said chambers being open on the air intake side and closed by fine mesh wire gauze on the throttle side and means for leading fuel to the mixing and atomizing chamber located nearest to said air intake. 4

6. A carburetor as set forth in claim 1 in which the means for leading fuel to the mixing and atomizing chamber comprises a conduit of multiple diversions, a bushing therein, a valve-needle located in said conduit having a generatrix in accordance with a curved line and forming with the inner wall of said bushing a circular opening whose cross sectional area is variable and means for varying said cross sectional area in accordance with the movements of said 5 throttle.

IGNAZ SCHORSCH.
